UNITED STATES PATENT OFFICE.

THOMAS S. PUKEURUD, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROLLER MECHANISM.

1,299,778.

Specification of Letters Patent.

Patented Apr. 8, 1919.

Application filed May 20, 1916. Serial No. 98,796.

To all whom it may concern:

Be it known that I, THOMAS S. PUKEURUD, a citizen of the United States, and a resident of Wilkinsburg, in the county of Allegheny and State of Pennsylvania, have invented a new and useful Improvement in Controller Mechanisms, of which the following is a specification.

My invention relates to controller mechanisms such as are employed in connection with electric motors, and it has for its object to provide a device of the character indicated which may be operated either by a power device or manually, at the will of the operator.

In the operation of controllers that are actuated by pilot motors or other power devices, it is sometimes necessary or desirable to adjust the controllers by manually operable means. This is especially true with reference to controllers that are employed in connection with motors for operating printing presses. The controller constituting the subject-matter of the present invention is particularly adapted to be employed for the purpose above mentioned.

I provide a controller that is adapted to be operated normally by a pilot motor. The motor is operatively connected to the movable member of the controller by gear mechanism comprising a pivotally mounted segmental gear wheel. The gear wheel is provided with a handle by means of which it may be actuated into and out of engagement with a coacting gear wheel in order that the controller may be actuated manually or by the power device, as desired.

In the accompanying drawing, Figure 1 is a plan view of a controller constructed in accordance with my invention, parts being broken away. Fig. 2 is a side view, partially in elevation and partially in section, of the mechanism of Fig. 1, parts being omitted for the sake of clearness.

A base plate 1 of suitable insulating material supports a series of stationary contact members 2. Movable contact members 3, which coact with the stationary contact members 2, are carried by arms 4 which may be, for example, three in number, when employed in connection with three-phase circuits. In the present instance, only two arms are shown in Fig. 1, the third arm being concealed by the gear mechanism. The arms 4 are secured to, and insulated from, a

member 5 that is rotatably mounted on a shaft 6.

A pilot motor 7, which may be, for example, an electric motor, is operatively connected to the member 5 by means of a worm 8, a worm wheel 9, a pinion 10 that is secured to the worm wheel 9 and a segmental gear wheel 11. The segmental gear wheel 11 is pivotally connected to the member 5 by means of a rod 12 in such manner that the gear wheel may be moved laterally into and out of engagement with the pinion 10. A spring 13 normally retains the gear wheel 11 in engagement with the pinion 10 to complete the operative connection between the motor and the movable members of the controller. A handle 14 is mounted upon the gear wheel 11 for actuation by the operator in order that the disengagement of the gear wheel 11 and the pinion 10 may be effected and that the controller may be adjusted manually while the gear mechanism is disconnected.

In the normal operation of the device, the controller is adjusted by completing the circuit of the motor in such manner as to cause the actuation of the arms 4 in the desired direction to adjust the resistance in the circuits controlled by the respective arms. In case the circuit of the motor is not opened by the operator, limit switches 15 open the motor circuit when one of the arms 4 has reached the end of its path of travel in either direction. An electromagnetic brake 16 frictionally engages a wheel 17 on the shaft of the pilot motor 7 when the circuit of the latter is open. An auxiliary relay 18 is controlled by a cam 19 that is secured to one of the movable arms 4. The electrical circuits controlled by the various contact members and switch members illustrated in the drawing are neither shown nor described since they constitute no part of the present invention and are not necessary to a clear and definite understanding of the same.

In case it is desired to adjust the controller manually or to change the relation of the controller to the pilot motor 7, the segmental gear wheel 11 may be actuated downwardly, as viewed in Fig. 2, until it occupies the position indicated by dotted lines. The gear wheel 11 is thus disengaged from the pinion 10, and the arms 4 may be adjusted to any desired position by the manual actuation of the handle 14. Upon the release of the han-

dle 14 by the operator, the gear wheel 11 is returned to its normal position in engagement with the pinion 10 by the spring 13 which was placed under tension by the disengagement of the gear wheels above described.

The arrangement above described is particularly adapted for use in connection with printing presses, but it is also capable of being employed in connection with other mechanisms in which similar operating characteristics are desirable.

I claim as my invention:

1. In a controller, the combination with a movable arm and a power device, of a member connected to said arm and movable into and out of adjustable connection to said power device, and a handle connected to said member for manually operating said arm.
2. In a controller, the combination with a movable member and a power device, of means comprising a pivotally mounted element for operatively connecting said device to said movable member, and an operating handle for actuating said element out of operative relation to said device and for actuating said movable member.
3. In a controller, the combination with a movable contact member, a motor and gear mechanism for operatively connecting said motor to said contact member, of manually operable means for actuating one member of said gear mechanism out of operative relation to said motor and for actuating said contact member.
4. In a controller, the combination with a movable arm, a pivotally mounted gear wheel connected thereto and a handle on said gear wheel for actuating it about its pivotal support and for actuating said arm, of a motor and means for operatively connecting the motor to the gear wheel.
5. In a controller, the combination with a movable arm and a motor, of gear mechanism for operatively connecting said motor to said arm, said mechanism comprising a pivotally mounted segmental gear wheel, a co-acting gear wheel, a spring for normally maintaining the operative relation of said

gear mechanism, and a manually operable handle for actuating said segmental gear wheel out of mesh with the coacting gear wheel and for actuating said arm.

6. The combination with a movable element and means for moving it, of a member pivotally connected to said movable element and adapted to move into and out of operative connection with said moving means, and means for yieldingly maintaining said member in operative connection with said moving means.

7. The combination with a movable element and a power device for actuating it, of means for operatively connecting said device to said element comprising a rotatable member and a member pivotally connected to said element for detachably engaging said member.

8. The combination with a movable element and a power device, of a pair of gear wheels respectively operatively connected to said element and to said power device, and releasably connected to each other and manually operable means for actuating one of said gear wheels out of operative relation to said other gear wheel, and for actuating said element.

9. The combination with movable means and means for moving it, of means for adjustably connecting said moving means to said movable means and adapted to actuate said movable means independently of said moving means.

10. In a controller for electric machinery, the combination with a movable contact member, of a pilot motor, a segmental member permanently connected to said contact member and adapted to be operatively connected to said pilot motor to cause said pilot motor to actuate said contact member, and means for disconnecting said segmental member from said pilot motor and for actuating said contact member independently of said pilot motor.

In testimony whereof, I have hereunto subscribed my name this 28th day of April 1916.

THOMAS S. PUKERUD.
